UNITED STATES PATENT OFFICE.

CHARLES A. KUTCHER, OF SHERIDAN, WYOMING.

SHOCK ABSORBER.

Application filed December 5, 1921. Serial No. 519,989.

To all whom it may concern:

Be it known that I, CHARLES A. KUTCHER, a citizen of the United States, residing at Sheridan, in the county of Sheridan 5 and State of Wyoming, have invented certain new and useful Improvements in Shock Absorbers; and I do declare the following to be a full, clear, and exact description of the invention, such as will enable others skilled in the art to which it 10 appertains to make and use the same.

This invention relates to an improved shock absorber to be used upon automobiles and other similar vehicles and is intended 15 to be connected with the frame and axle of the automobile so that when the frame or body portion moves downwardly in going over rough places in a road and then rebounds, the rebound will be checked and 20 thus jolting of the car prevented.

One object of the invention is to so construct this device that it may be readily applied to an automobile having a conventional construction and to have the device 25 so constructed that it will not interfere with downward movement of the body portion of the car but will retard upward movement of the body portion of the car. It will thus be seen that in going over rough roads, the 30 body portion of the car may readily move downwardly toward the axle but will move upwardly slowly on the rebound and thus prevent the jolting.

Another object of the invention is to so 35 construct this device that it may have an operation similar to that of a brake such as is ordinarily used upon the rear axle of a car, it being understood however that the frictional binding between the drum portion 40 of the device and drum encircling ring about which the gripping band is placed will not be sufficient to entirely prevent rotation of the ring upon the drum.

Another object of the invention is to so 45 construct the drum portion of this device that it may be compressed thus preventing excessive binding between the ring and drum when going over very rough places in a road.

Another object of the invention is to so 50 construct this drum portion that it may be yieldably held against compression by means of a spring element which is so mounted that its tension may be controlled

and the proper binding between the drum 75 and drum encircling ring provided.

Another object of the invention is to so construct this device that the ring which fits upon the drum and the gripping band which extends about the ring may be held against 80 movement transversely of the drum and thus prevented from slipping transversely out of place, the guide means however permitting of proper movement of the ring and band.

This invention is illustrated in the accompanying drawings, wherein:

Figure 1 is a view showing the device applied to a fragmentary portion of a vehicle, the view being principally in side elevation and partially in section. 70

Figure 2 is a sectional view taken along the line 2—2 of Fig. 1.

Figure 3 is a sectional view taken along the line 3—3 of Fig. 1.

This improved shock absorber is to be 75 connected with the axle 1 and with a convenient portion of the chassis 2, a fragment of which has been shown in Figs. 1 and 2. The drum 3 which is formed of metal and preferably of spring metal is in 80 the form of a split ring having one end portion bent to extend inwardly and provide an abutment tongue 4 thus permitting the drum to be expanded and to permit compression of the drum to be controlled as will 85 be hereinafter brought out. This drum carries an attaching bracket or support 5 which is bolted to the side bar of the chassis by means of bolts 6 and is provided with arms 7 at its ends which are secured to the drum 90 as shown by means of rivets or other similar fasteners 8. From an inspection of Fig. 1, it will be seen that this attaching bracket or carrier 5 is connected with one end portion 95 of the split ring which forms the drum and with the split ring intermediate its length thus leaving the split ring above the bracket free to expand and contract. An L-shaped bracket 9 is riveted to the bracket or support 5 and has its outstanding foot 10 provided with an opening through which will 100 pass a threaded stem 11. After the stem 11 has been passed through the opening in the foot 10 of the bracket 9, the securing nut 12 will be put in place and tightened and 105 the abutment nut 13 will then be placed upon this stem. A spring 14 is placed upon the stem and has its lower end engaging the

abutment nut 13 and its upper end engaging the inwardly extending tongue 4 of the split ring which forms the drum. From an inspection of Fig. 1, it will be readily seen that by turning the abutment nut 13, the tension of the spring 14 can be readily controlled and the spring 14 by bearing against the tongue 4 caused to yieldably prevent compression of the upper portion of the drum to the extent desired. A facing strip 15 which will be formed of any suitable material to create frictional binding is placed upon the outer face of this drum forming split ring and is secured by rivets 16. If this facing should wear out, it can be easily removed and a new one put in place.

The gripping band 17 extends about a ring 18 which fits upon the drum and is free to turn upon the drum. When this band is drawn into tight engagement with the ring, the band and ring will be caused to rotate as a unit upon the drum but when the band is released, the ring and band may have independent movement. It will thus be seen that when the lever 19 which has loose connection with the two end portions of the band as shown at 20 and 21, is moving in one direction the band and ring may move freely about the drum whereas when the lever is having movement in the opposite direction, the band will be drawn tightly about the ring and pressure applied to draw the ring into tight binding engagement with the frictional facing of the drum. In order to yieldably hold the lever against movement towards the releasing position, there has been provided a spring 22 which has one end connected with the lower portion of the lever and has its lower end portion connected with an ear 23 secured to the gripping band. It is desired to prevent the gripping band and ring from having movement transversely of the drum and therefore the band has been provided with yokes 24 which are secured to the band by rivets 25 and have their side arms extending along the edges of the band, ring and drum. From an inspection of Fig. 3, it will be readily seen that the yokes will prevent the ring and band from having movement which would permit of them slipping off of the drum but that these yokes will not prevent free movement of the band and ring about the drum. The forward end portion of the lever 19 is connected with a rigid strap 26 by means of a hinged joint as shown at 27 and it will thus be seen that when the frame of the car moves up and down as the vehicle passes over a rough road, this lever may have vertical swinging movement to bring the gripping band into and out of gripping engagement with the ring. The lower end of this strap or standard 26 is connected with the axle 1 by means of a clamp 28.

When the shock absorber is in use, one will be put in place adjacent each of the wheels and each will be connected with the chassis and with the adjacent end portion of an axle. The strap or standard 26 will be connected with the axle by means of the clamp 28 and the support or carrier 5 will be riveted to the side bar of the chassis. When the car is moving over a rough road and the car moves downwardly, the lever 19 will swing against the action of the spring 22 thus releasing the gripping band and permitting the band and ring 18 to move freely about the drum. It will thus be seen that downward movement of the car body against the action of the usual supporting spring will not be retarded. When the car moves upwardly on the rebound, the upward movement of the car body and chassis will cause the lever to swing in the direction to draw the end portions of the band toward each other thus tightening the gripping band about the ring and causing the ring to be drawn into tight binding engagement with the friction facing of the drum. This will serve to retard upward movement of the car body but will not entirely prevent this movement and therefore the car may return to its original position but will be prevented from causing jolting. In going over very rough roads, the tendency for upward rebound will be greater than in going over slightly rough roads but since the upper portion of the split ring which forms the drum may be compressed against the action of the spring 14, the proper amount of frictional binding between the ring and drum may be maintained at all times. If it is found that the spring 14 is under too great a tension or does not have sufficient tension to cause proper operation of the compressible section of the drum, it is simply necessary to adjust the abutment nut 13 upon the threaded stem 11 and the tension of the spring can be controlled. There has thus been provided a shock absorber for use in connection with a vehicle which will serve to effectively prevent excessive rebound of the car and will prevent jolting of the occupants of the car.

I claim:

1. A shock absorber comprising a drum element, a ring fitting about the drum for turning upon the drum in either direction when ungrasped, a gripping band extending about said ring, and means for drawing the band tightly about the ring whereby the ring and band may be moved about the drum in one direction as a single unit when said means is moved in an operative direction, the band having movement upon said ring and the ring being permitted of movement independent of the band when the means is moved in an opposite direction.

2. The structure of claim 1 having a fric-

tion element between the drum and ring for causing frictional binding to retard turning of the ring about the drum.

3. The structure of claim 1 having a friction element between the drum and ring for causing frictional binding to retard turning of the ring about the drum said friction element being secured upon the outer face of the drum.

10 4. The structure of claim 1 and guides carried by the gripping band and extending along the sides of the drum to hold the band and ring against moving transversely of the drum.

15 5. The structure of claim 1 having the drum compressible radially to overcome excessive binding between the ring and drum when the gripping band is tightened.

6. The structure of claim 1 having the 20 drum formed of resilient material and split transversely whereby the drum may be compressed when the band is drawn tight and the band and ring moved as a unit about the drum.

25 7. The structure of claim 1 having the drum formed of resilient material and split transversely to provide a compressible drum having spaced ends, a support connected with one end portion of the drum, and re-

30 silent means carried by said support and

engaging the second end portion of the drum to yieldably hold the drum against compression.

8. The structure of claim 1 having the drum formed of resilient material and split 35 transversely to provide a compressible drum having spaced ends, a support connected with one end portion of the drum, resilient means carried by said support and engaging the second end portion of the drum to 40 yieldably hold the drum against compression, and means for varying the tension of said resilient means.

9. The structure of claim 1 having the drum formed of resilient material and split 45 transversely to provide a compressible drum having spaced ends, a support extending diametrically of the drum and having one end connected with one end of the drum and having its other end connected with the drum 50 at a point intermediate the ends of the drum, a tongue extension at the other end of said drum, a pin carried by the support, an abutment adjustable longitudinally upon the pin, and a spring upon the pin having one end 55 engaging the abutment and its other end engaging the tongue extension of the drum.

In testimony whereof I have hereunto set my hand.

CHARLES A. KUTCHER.
